UNITED STATES PATENT OFFICE.

CHARLES J. REPATH, OF LOS ANGELES, CALIFORNIA.

FLOUR SIFTER.

Application filed May 23, 1922. Serial No. 563,152.

To all whom it may concern:

Be it known that I, CHARLES J. REPATH, a citizen of the United States, residing at Los Angeles, in the county of Los Angeles and State of California, have invented a new and useful Flour Sifter, of which the following is a specification.

This invention relates to flour-sifters and is particularly directed to a type of device 10 in which the flour, meal, or similar substances may be repeatedly sifted before being discharged therefrom.

An object of the invention is to provide a sifter of the above character in which the 15 entire operating mechanism is carried by a single member and in which said member constitutes a means for reversing the sifter.

Another object is to provide a sifter having a tubular handle and a reversing member 20 journaled therein and extended outwardly as an extension of the handle providing a hand grip portion by which the member is manipulated, and providing an operating shaft associated with an agitator 25 within the sifter and extending through said member for manual rotation.

Various other objects and advantages will be more fully apparent from the following description of the accompanying drawings, 30 which form a part of this disclosure, and which illustrate a preferred form of embodiment of the invention.

Of the drawings:

Figure 1 is a plan view of my improved 35 sifter, with one of the cover members removed.

Fig. 2 is a section on line 2—2 of Fig. 1.

Fig. 3 is a section on line 3—3 of Fig. 1.

Fig. 4 is a detail section on line 4—4 of 40 Fig. 2.

Fig. 5 is a perspective view of one of the cover members.

Referring to the drawings; 1 designates a cylindrical hollow body open at its opposite 45 ends and provided at its medial portion with a tubular handle 2 normal to the axis of the body, and 3—4 designate cover members closing the body.

Journalized in the tubular handle 2 is a reversing member 5 in the form of a cylindrical plug, preferably constructed of wood and extended outwardly to form an extension of the handle and provided with a hand-grip 6 for manual manipulation of the 55 member 5. The inner end of the member 5

is flush with the interior surface of the body wall and carries a sifter member comprising a circular ring 7 closely contacting the wall of the body with its ends 8 driven into the member 5, and a foraminous hemispherical element 9 forming a partition across the body 1. Associated with the sifter member is a rotary agitator comprising hemispherical arms 10 which are carried upon the inner end of an operating shaft or rod 11 60 journaled in the member 5 and extending through one side of the foraminous element 9. The shaft 11 extends through the member 5 and its outer end is bent in the form of a crank having a knob 12 at its outer end 65 to facilitate a manual rotation of the shaft.

The member 5 is limited in its rotation to one-half of a revolution, by a screw 13 carried by said member and engaging through a slot 14 in the tubular handle 2. 70

With the device as shown in Fig. 2, the cover 3 will be removed and a quantity of flour or other material placed into the chamber 15. The cover 3 will then be replaced and the shaft 11 rotated to sift the material 80 through the foraminous sifter member 9 into the chamber 16.

When all the material has been sifted into the chamber 16, the reversing member 5 will be rotated one-half of a revolution 85 to position the sifting member 9 on the opposite side of the agitator 10, (as indicated in dotted lines in Fig. 3) and the entire device will then be turned over, the material in the chamber 16 dropping upon the 90 sifter member 9.

The shaft will again be rotated to sift the material a second time through the foraminous sifter member 9 and into the chamber 15, this operation being repeated until the 95 material has been sifted a desired number of times, when one or the other of the covers 3—4 may be removed for the purpose of discharging the material from the sifter.

In the device described above, I have provided a reversible flour-sifter of cheap, strong, and durable construction, which may be operated with maximum ease and speed, and in which the operating shaft and sifter member have no direct bearing in the walls 100 of the body such as would require the walls to be apertured to receive them, this being important as it is evident that such apertures and their engaging parts are not usually in this type of device, constructed with 105 110

such care as to prevent leakage of the flour therethrough, and further the construction illustrated herein permits a maintaining of the smooth exterior surface of the body.

5 It will be noted that excepting for the tubular handle the entire body is free from any aperture or perforation, and with the long plug member 5 closely fitting in the handle it will be plain that leakage of the 10 material or dust due to the sifting thereof is effectively prevented.

While the form of device herein illustrated and described is well adapted for the purposes primarily stated, it is to be understood that the invention is not to be limited 15 in this regard, for it is susceptible of embodiment in various other forms such as come within the scope of the following claims.

20 I claim:

1. In a device of the nature disclosed, a cylindrical body having a laterally extended tubular handle, a reversing member journaled in said handle, an operating shaft journaled in said member and extending exteriorly for manual rotation, an agitator secured upon the shaft within the body, a foraminous sifter member secured to the reversing member and forming a partition 25 across the body on one side of the agitator, the reversing member being operable to alternately position the sifter member on opposite sides of the agitator.

2. In a device of the nature disclosed, a cylindrical body having a laterally extended tubular handle, a reversing member journaled in said handle, an operating shaft journaled in said member and wholly supported thereby, said shaft extending 30 exteriorly for manual rotation and inwardly into the body, an agitator secured upon the shaft within the body, a foraminous sifter member wholly supported upon the reversing member and forming a partition across 35 the body on one side of the agitator, and means between the tubular handle and the reversing member limiting the rotation of said member to one-half of a revolution, the reversing member being operable to alternately 40 position the sifter member on opposite sides of the agitator.

3. In a device of the nature disclosed, a cylindrical body having a laterally extended tubular handle, a reversing member journaled in said handle and extended outwardly therefrom to form an extension of the handle and to provide a hand-grip portion 55 for manual manipulation of said member, an operating shaft journaled in the reversing member and extending into the body, the outer end of said shaft extending exteriorly for manual rotation, an agitator secured to the shaft within the body, a foraminous sifter member carried by the reversing member and extending across the 60 body to form a transverse partition on one side of the agitator, and means limiting the movements of the reversing member to one-half of a revolution whereby said member may be operated to alternately position the 65 sifter member on opposite sides of the agitator.

4. In a device of the nature disclosed, a cylindrical body having opposite open ends and provided with a laterally extended tubular handle at its medial portion, removable cover members for closing the ends of the body, a reversing member journaled in the tubular handle and extended outwardly therefrom to form an extension of the handle and provide a handgrip portion for 75 manual manipulation of said member, means permitting only a half rotation of said member, an operating shaft journaled in said member and extending into the body, the outer end of the shaft extending exteriorly and bent to form a crank for manual rotation of the shaft, a rotary agitator carried by the shaft within the body, a foraminous sifter member of approximately hemispherical form carried by the reversing member and forming a partition in the body 80 on one side of the agitator, the reversing member being operable to alternately position the sifter member on opposite sides of the agitator.

Signed at Los Angeles, Calif., this 16th day of May, 1922.

CHARLES J. REPATH.
